(57) **CLAIM**

The ornamental design for a display panel portion with an animated icon, substantially as shown and described.

DESCRIPTION

FIG. 1 is a first image in a sequence for a display panel portion with an animated icon, showing our new design.

FIG. 2 is a second image in the sequence thereof.

FIG. 3 is a third image in the sequence thereof.

FIG. 4 is a fourth image in the sequence thereof.

FIG. 5 is a fifth image in the sequence thereof.

FIG. 6 is a sixth image in the sequence thereof.

FIG. 7 is a seventh image in the sequence thereof.

FIG. 8 is an eighth image in the sequence thereof; and,

FIG. 9 is a ninth image in the sequence thereof.

The appearance of the transitional image sequentially transitions between the images shown in FIGS. 1-9. The process or period in which one image transitions to another image forms no part of the claimed design.

The order, the process or the period, in which one image transitions to another image forms no part of the claimed design. The broken lines showing a portion of a display panel and portions of the animated computer icon, including stippled portions, in FIGS. 1-9 form no part of the claimed design.
